(57) **CLAIM**

The ornamental design for a toy brick with an upstanding platform as shown and described.

DESCRIPTION

FIG. 1 is a first top perspective view of a toy brick with an upstanding platform.

FIG. 2 is a bottom perspective view of the toy brick with an upstanding platform.

FIG. 3 is a front plan view of the toy brick with an upstanding platform.

FIG. 4 is a back plan view of the toy brick with an upstanding platform.

FIG. 5 is a left side plan view of the toy brick with an upstanding platform.

FIG. 6 is a right side plan view of the toy brick with an upstanding platform.

FIG. 7 is a top plan view of the toy brick with an upstanding platform.

FIG. 8 is a bottom plan view of the toy brick with an upstanding platform.

FIG. 9 is a second top perspective view of the toy brick with an upstanding platform.

FIG. 10 is a first top perspective view of a second embodiment of the toy brick with an upstanding platform.

FIG. 11 is a bottom perspective view of the second embodiment of the toy brick with an upstanding platform.

FIG. 12 is a front plan view of the second embodiment of the toy brick with an upstanding platform.

FIG. 13 is a back plan view of the second embodiment of the toy brick with an upstanding platform.

FIG. 14 is a left side plan view of the second embodiment of the toy brick with an upstanding platform.

FIG. 15 is a right side plan view of the second embodiment of the toy brick with an upstanding platform.

FIG. 16 is a top plan view of the second embodiment of the toy brick with an upstanding platform.

FIG. 17 is a bottom plan view of the second embodiment of the toy brick with an upstanding platform; and,

FIG. 18 is a second top perspective view of the second embodiment of a toy brick with an upstanding platform. The broken lines in the figures show features of the toy brick with an upstanding platform that form no part of the claimed design.
